UNITED STATES PATENT OFFICE.

LOYD PINKNEY CARPENTER, OF PALESTINE, TEXAS.

SPARK PLUG.

Application filed October 19, 1920. Serial No. 417,880.

To all whom it may concern:

Be it known that I, LOYD PINKNEY CARPENTER, a citizen of the United States, residing at Palestine, in the county of Anderson 5 and State of Texas, have invented certain new and useful Improvements in Spark Plugs, of which the following is a specification.

This invention relates to improvements in 10 spark plugs.

An important object of this invention is the provision of a spark plug so constructed as to eliminate the constant necessity of 15 cleaning the sparking parts of carbon deposits.

A further object of the invention is the provision of a spark plug so constructed as to intensify the spark in order to explode a relatively low grade of combustible vapor.

20 A further object of the invention is the provision of a spark plug which has a plurality of adjustable sparking points arranged to provide a relatively large degree of surface over which the spark must travel 25 to insure a proper ignition of fuel.

Other objects and advantages will be apparent during the course of the following detailed description.

In the accompanying drawings forming 30 a part of this specification, and in which like reference characters designate like parts throughout the same.

Figure 1 is a side elevation of the improved spark plug.

35 Figure 2 is a cross sectional view taken through the improved spark plug and showing the sparking arrangement.

Figure 3 is a bottom plan view of the spark plug showing the sparking points.

40 In the accompanying drawings, wherein for the purpose of illustration is shown a preferred embodiment of my invention, the numeral 5 designates a body casing, formed preferably of standard spark plug construction, and which has the screw threads 6 thereon adapted to be threaded into the head of an internal combustion engine cylinder, and having the internal annular seat 7 therein. An insulating core 8 is provided, having the annular shoulder 9 thereon which is adapted to rest upon the annular seat 7 of the body casing. It is preferred that the insulating core 8 differ from the ordinary spark plug construction, in that the sides

10 contact with the interior of the body casing 5 and the bottom 11 thereof is flush with the bottom 12 of the body casing, thus eliminating the cavity intermediate the casing and insulating core and in which carbon is sometimes deposited. A clamping nut 13 is 55 provided and adapted to bind against the shoulder 9 to maintain the insulating core 8 in position with respect to the body casing. It is preferred that the washers 14 be provided intermediate the binding points 60 adjacent the insulating core 8.

The main electrode 15 is centrally disposed within the insulating core 8 and has the screw threaded projection 16 thereon, provided to receive a thumb screw 17 for 70 the purpose of clamping a terminal 18 of a cable 19 which leads to a battery or the like. Upon the lower end of the electrode 15, a multi-pointed head 20 is preferably 75 integrally formed, and projects for a short distance from the bottom 11 of the insulating core. Neutral electrodes 21 are provided intermediate the head 20 and the outer surface of the insulating core and which are so situated that each one of them has a respective point 22 at its shortest distance to the head. A plurality of electrodes 23 are grounded in the body casing 5 and which project from the bottom 12 of the casing 5 each having an inturned head 24 arranged 85 tangentially to the plug axis, the upper edge of which is just flush with the bottom of the main and neutral electrodes.

In the construction of the spark plugs here illustrated, it is preferred that the head 90 20 have five points thereon, co-acting with the five neutral electrodes 21 and which in turn co-act with the five ground electrodes 23.

Since the insulating core 8 can be rotated within the casing 5, it can be readily seen 95 that the shortest distance between any neutral electrode 21 and its respective ground electrode 23 can be varied. Thus, a battery or exciter of varying voltage can be used, and the spark plug adjusted to suit the voltage. The spark thus produced within the cylinder will travel over a considerable distance, since each spark pursues a zig zag course from the main and ground electrodes to its respective neutral electrode 21.

100 It is to be understood that the form of my invention herewith shown and described is to be taken as a preferred example of the

same, and that various changes in the shape, size and arrangement of parts may be made without departing from the spirit of the invention or the scope of the subjoined claims.

I claim:

1. A spark plug comprising a metal body casing, an insulating core, a plurality of ground electrodes carried by the casing in depending relation therefrom, a main electrode carried by the insulating core having a depending multi-pointed head thereon, a point being provided for each ground electrode, and a plurality of neutral electrodes relatively insulated from each other and carried by said core in depending relation, a neutral electrode being provided for each point of the multi-pointed head and being placed between its respective point of said multi-pointed head and one of the neutral electrodes whereby during operation a spark may first jump from the point of the main electrode head to its respective neutral electrode and then to the ground electrode adjacent the same, said core being adjustable in the body casing whereby the distances be-

tween the ground electrodes and their respective neutral electrodes may be varied.

2. A spark plug comprising a body casing, an insulating core, a plurality of ground electrodes carried by said casing in depending relation therefrom having their lower ends inturned below the bottom of said core in tangential relation with respect to the plug axis, a main electrode carried by said core having a multi-pointed head embedded in and depending below the bottom of said core and having a point provided thereon for each ground electrode, and neutral electrodes separably carried by said core in insulated relation depending from the bottom thereof, a neutral electrode being provided for each point of the main electrode head, each neutral electrode having its respective point on the multi-pointed head located at the shortest distance between said neutral electrode and said head, said core being movable in the body casing whereby to vary the distance between the neutral electrodes and the inturned ends of their respective ground electrodes.

LOYD PINKNEY CARPENTER.
